UNITED STATES PATENT OFFICE.

CHARLES W. STEVENS, OF EAST ORANGE, NEW JERSEY.

WIRE-HAT-FRAME MACHINE.

No. 861,326.

Specification of Letters Patent.

Patented July 30, 1907.

Application filed April 14, 1906. Serial No. 311,695.

To all whom it may concern:

Be it known that I, CHARLES W. STEVENS, a citizen of the United States, residing at East Orange, Essex county, New Jersey, have invented certain new and useful Improvements in Wire-Hat-Frame Machines, of which the following is a full, clear, and exact description.

My invention relates to wire hat frame machines.

One object of my invention is to provide a machine upon which wire hat frames of any form may be made more rapidly than on machines previously in use.

A second object is to provide means for readily releasing the completed frame.

A third object is to provide means for readily copying the shapes of hats made from felt or other materials.

A fourth object is to provide means for copying a shape on a form for transferral to other machines from which duplicate forms may be set up.

The invention consists in improvements, the principles of which are illustrated in the accompanying three sheets of drawings.

Figure 1 is a side elevation of a machine embodying all the improvements of my invention. Fig. 2 is an enlarged view partially in section, showing parts of the apparatus for forming a single hat. Fig. 3 is a detail plan view of the cross bars for clamping the adjustable holding arms in place. Fig. 4 is a sectional detail view of the end of one of the adjustable arms, showing an auxiliary tip. Fig. 5 is a view similar to Fig. 2, but showing the upper part of the machine for copying hat frames formed on the lower part and also for assisting in the formation of hats of unusual shape. Fig. 6 is a detail horizontal sectional view of the cross bars of the upper forming mechanism shown in Fig. 5. Fig. 7 is a detail plan and sectional view of a collar for supporting the arm-carrying brackets.

1 is the base, of suitable material, carrying an upright tube or hollow post 2, preferably of metal. 3 is a collar rotatably supported on the post 2 and having a limited vertical play. A series of brackets, such as 4, are pivoted to collar 3 and have extensions 5 which carry sets of pivoted arms. These arms are preferably formed in two sections 6 and 7, which telescope relative to one another and are guided relative to each other by clips 45 such as 8-8.

9 is a cross bar secured to and forming a part of the bracket 4 at the upper end, and having a longitudinal centrally located slot similar to the slot in the clamp bar 10. The arms are flat and extend between the 50 cross bar 9 and the clamp bar 10.

11 is a thumb nut for clamping bar 10 toward bar 9 so as to hold the arms securely in position.

A second series of adjustable telescopic pivoted arms are carried by the bracket 4 on the opposite side to the 55 arms composed of the parts 6 and 7. Each of the members of this second set of arms is composed of telescopic

members 12 and 13 guided by clips 14 relative to each other.

15 is a cross bar somewhat similar to bar 9 and carried by and forming a part of the bracket 4. 60

16 is a clamp bar which may be forced toward bar 15 for the purpose of clamping the arms by means of clamping devices 17-17.

Each of the bars 9, 10, 15 and 16 are provided with longitudinal slots such as the slots 17'. The upper 65 ends of some of the arms carry auxiliary tips 18, as shown in Fig. 4.

19 is a clamp nut on the stud 20, for the purpose of clamping the tip 18 to the arm member 7.

Each arm member 7 is preferably provided with a 70 perforation 20' so that an auxiliary tip may be secured thereto. Each of the arms and the auxiliary tip members are provided with notches, as indicated at 21, facing outward and upward.

It will be seen from the description thus far that each 75 of the arms may be extended or made of the necessary length to bring the notched end into the position necessary for holding the wire as desired. So also the arms may be swung on their pivots on the bracket for the purpose of varying the position of the end notch. In 80 this way it is possible to adjust any one of the arms independently of all the other arms, it simply being necessary to loosen the clamps, such as 11 and 17, sufficiently to allow the arm adjacent thereto to be adjusted. Of course the movement of any one of the arms between 85 the bars 9 and 10 toward or away from the axis of the supporting post 2 is limited by the position of the adjacent arms. When this limitation prevents operation in the desired manner, one of the arms between the adjacent bars 15 and 16 may be adjusted to meet the condition required. 90

22 is a collar connected to the bracket 4 by links 23-23 and vertically held between the two clamp rings 24 and 25.

The apparatus thus far described, so far as the actual 95 formation of any ordinary hat is concerned, is complete, and, indeed, hats may be formed upon such mechanism. To more readily facilitate the removal of the completed frame from the machine, I prefer to provide mechanism for simultaneously releasing all of 100 the arms which support the wire of the frame. 26 is a rod vertically movable in post 2 and having secured to it a ring 27 by means of screws 28-28. These screws pass through vertical slots 29-29 in the post 2 so that the rod 26 and the supporting ring 27 may be moved 105 upward from the position shown in Fig. 2. This upward movement carries the collar 3 and the lower ends of all the brackets 4-4. Such upward movement of the collar 3 causes the upper ends of the brackets to be moved toward the axis of the post by reason of the 110 connecting links 23-23. Such action instantly releases the wire frame (not shown) from the supporting arms.

The upward movement of rod 26 may be accomplished in any manner, but I prefer the construction shown in Fig. 1. In this figure, 30 is a pedal hinged or pivoted to the base 1 of the machine and connected to lever 31 by link 32. Lever 31 is pivoted at 30° and connected by a push link 33 to the lower end of rod 26. Depression of the pedal 30, therefore, raises the rod 26 and will release the hat frame from the arms.

34 is a post carried by the base 1 and having a telescoping extension 35.

36 is a cross bar rotatable in a horizontal plane at the top of extension 35 and supporting the hollow post or tube 37.

38 is a collar vertically movable on the post 37 and also rotatable and carrying a series of pivoted brackets 39-39. These brackets have extensions, such as 40, to which are pivoted a series of telescopic arms made up of the portions 41 and 42.

43-43 indicate guide clips for relatively positioning the two portions 41 and 42 of the arms.

The outer end of the bracket 39 has formed as a part of it a cross bar 44.

45 is a clamp bar secured to the bracket by bolt 46.

47-47 indicate clamping devices, by means of which the bars 44 and 45 are drawn toward each other so as to clamp the arms which are located between them. Each of the bars 44 and 45 are provided with longitudinal slots, such as 47', so that the clamping devices may be moved longitudinally to accommodate the necessary adjustment of the arms. The end of each arm is notched, as at 48, and also preferably perforated, as at 49, similar to the arms heretofore described and for the same purpose.

50 is a collar carried by the post 37 and connected to the brackets 39-39 by links 51-51 and vertically positioned between the clamp rings 52 and 53.

54 is a ring.

55 indicates a screw which passes through the ring 54 and through a vertical slot 56 in the post 37 and takes 40 into the vertically movable plug 57. This plug 57 is connected by a wire 58 to the cross lever 59 at the top, and is supplied with a cotter pin 60. Lever 59 is pivoted at 61 and connected by a rod 62 to the rear end of lever 31 at the base, by means of a link 63 similar to 45 link 33.

The arms of the upper set shown in Fig. 5 may be extended and adjusted similar to the arms of the lower set and brought into play for providing a holding position for the wire in the formation of hats of unusual 50 shape. A great many hats which cannot be formed on the ordinary machine can be formed by the use of one of these overhanging mechanisms. By means of the connection to the lever 31, just described, the depression of the pedal 30 releases all of the arms of the upper set at the same time that it releases all of the arms of the lower set. By means of these oppositely positioned sets of arms, shown in Fig. 1, it is possible to adjust one set to be the opposite or reverse of the other. In this way, for instance, let us suppose that the lower 60 set is adjusted and the hat formed thereon. The upper set may then be brought into play and adjusted with its arms in corresponding positions. This upper set may then be swung to one side and left in that form, so that afterwards the manufacturer can use it 65 as a model to aid him to readjust the lower set if it has

been disarranged. A single standard hat may be adjusted on the lower set of arms. If then the upper set is brought into play, a sort of mold may be formed by adjusting the arms of the upper set to the proper shape. This skeleton mold may then be removed from the machine and applied to another machine, so that a lower set on this second machine may be arranged for duplication of the original model. This is of particular advantage where a great many hats of the same shape are to be made, in which case a number of machines would 70 be in use. It will be readily seen that the lower set of arms may be removed by simply loosening the two clamp rings 24 and 25. Similarly the upper set may be removed by taking off the clamp rings 52, 53 and 54. Both sets of arms may be freely rotated about their 80 axes for more readily reaching the different parts of the mechanism in forming the hat frame.

In case it is desired to copy a pattern from the upper arms, upon the lower arms it is obvious that the upper set of downward depending arms are adjusted and 85 then the hat formed thereon. The lower set of upwardly extending arms are then brought into play and adjusted with its arms in corresponding position and then said lower set of arms may be removed.

What I claim is:

1. A wire hat frame machine comprising, a series of movable brackets and a series of notched telescopic pivoted arms carried by each bracket.

2. A wire hat frame machine comprising, a series of movable brackets and two series of telescopic pivoted arms 95 carried by each bracket.

3. In a wire hat frame machine, a series of brackets, a pair of clamp bars carried by each bracket, a series of extensible arms carried by said bracket and extending between said bars, and clamp devices extending through 100 said bars between said arms.

4. In a wire hat frame machine, a series of pivoted notched arms, each arm being composed of two portions extensible relatively to each other, and means for independently clamping each arm in position.

5. In a wire hat frame machine, a longitudinally adjustable arm having an open notch in its outer end for holding a wire and a perforation adjacent thereto, and an auxiliary notched tip member adjustably pivoted in said perforation.

6. In a wire hat frame machine, a post, a collar vertically movable thereon, a series of brackets pivotally carried by said collar, adjustable arms carried by said brackets, and a link connection between said brackets and the upper end of said post.

7. In a wire hat frame machine, a pair of oppositely disposed similarly constructed sets of arms adjustable longitudinally toward each other.

8. In a wire hat frame machine, a set of adjustable upwardly extending wire holding arms, and a plurality of 120 downwardly extending adjustable wire holding arms located above the upwardly extending set.

9. In a wire hat frame machine, a set of upwardly extending adjustable arms, and a set of downwardly extending arms mounted on an axis adapted to swing laterally 125 relatively to the axis of the lower set.

10. In a wire hat frame machine, two sets of adjustable wire holding arms oppositely disposed and independently rotatable on their axes.

11. In a wire hat frame machine, two sets of oppositely disposed wire holding arms, and means for simultaneously releasing both sets, for the purpose specified.

12. In a wire hat frame machine, a vertical post, a lateral extension at the top carried thereby, a downwardly extending post carried by said extension, and a set of downwardly projecting adjustable wire holding arms rotatably carried by said depending post.

13. In a wire hat frame machine, a vertical post, a horizontal extension at the upper end thereof, a vertically de-

- pending post carried by said extension, said extension being adapted to swing, and a set of adjustable wire holding members carried by said depending post. 60
14. In a wire hat frame machine, a plurality of oppositely disposed holding members extensible longitudinally toward each other. 65
15. In a wire hat frame machine, a set of adjustable wire holding members, and means for mounting a copying set in position opposite said first set. 70
- 10 16. In a wire hat frame machine, a post, two collars removably mounted thereon, a series of brackets pivoted to one collar, a series of links connecting said brackets to the other collar, and adjustable wire holding members carried by said brackets. 75
- 15 17. In a wire hat frame machine, a vertical post, a lateral extension at the upper end thereof, a downwardly extending post carried by said extension, and a set of downwardly projecting wire holding arms rotatably carried by said depending post. 80
- 20 18. In a wire hat frame machine, a vertical post, a horizontal extension at the upper end thereof, a vertically depending post carried by said extension, said extension being adapted to swing, and a set of wire holding members carried by said depending post. 85
- 25 19. In a wire hat frame machine, a plurality of depending adjustable wire holding arms arranged around a vertical axis. 90
- 30 20. In a wire hat frame machine, a set of adjustable wire holding members, and a copying set of adjustable wire holding members arranged in position opposite the first set. 95
- 35 21. In a wire hat frame machine, a set of adjustable wire holding members, a copying set of adjustable wire holding members arranged in position opposite the first set, and means to permit the copying set to be moved out of its copying position. 100
- 40 22. In a wire hat frame machine, a set of radially arranged and movable wire holding members, and a copying set of radially arranged and movable wire holding members. 105
- 45 23. In a wire hat frame machine, a set of radially arranged and movable wire holding members, a copying set of radially arranged and movable wire holding members, and means for simultaneously moving all of the members of one set radially. 110
- 50 24. In a wire hat frame machine, a set of radially arranged and movable wire holding members, a copying set of radially arranged and movable wire holding members, and means for simultaneously moving all of the members of both sets radially. 115
- 55 25. In a wire hat frame machine, two sets of adjustable wire holding members arranged opposite each other and independently rotatable, one of said sets being also movable transversely relative to the other set. 120
- 55 26. In a wire hat frame machine, a post, an extension rotatable in a plane substantially at right angles thereto, a second post carried by said extension and arranged par-
- allel to the first post, and a set of longitudinally and radially adjustable wire holding arms carried by said second post. 60
27. In a wire hat frame machine, a post, an extension rotatable in a plane substantially at right angles thereto, a second post carried by said extension and arranged parallel to the first post, and a set of longitudinally and radially adjustable wire holding arms removably carried by said second post. 65
28. In a wire hat frame machine, a set of radially arranged brackets movable to and from the common axis, a plurality of longitudinally adjustable wire holding arms pivotally carried by each bracket, and means for clamping 70 said arms to said brackets.
29. In a wire hat frame machine, a set of radially arranged brackets movable to and from the common axis, a plurality of longitudinally adjustable wire holding arms pivotally carried by each bracket, means for clamping 75 said arms to said brackets, and means for simultaneously moving all of said brackets toward their common axis.
30. In a wire hat frame machine, a set of radially arranged brackets movable to and from the common axis, a plurality of longitudinally adjustable wire holding arms 80 pivotally carried by each bracket, means for clamping said arms to said brackets, and means for rotatably supporting said brackets.
31. The combination with a support, of a plurality of adjustable members mounted thereon for forming a hat 85 frame, a second support independent of said first named support, and means carried by said second support comprising a plurality of devices for predetermining the positions of said members.
32. The combination with a support, of a plurality of 90 adjustable members carried thereby and adapted to support a hat frame at different points about the periphery of said frame, a second support independent of said first named support, and means carried by said second support for predetermining positions of a plurality of said members. 95
33. The combination with a rotatably mounted support, of a plurality of independently adjustable members thereon, a second support pivotally mounted to move toward and away from said first named support, and means carried by said second support for determining the positions of said members. 100
34. The combination with a rotatably mounted support, of a plurality of independently adjustable members thereon, a second support movably mounted to move toward and away from said first named support, and means removably carried by said second support for predetermining the positions of said members. 105
